Attorney

UNITED STATES PATENT OFFICE.

ROBERT KEITH HALL, OF DENVER, COLORADO.

COLLAPSIBLE SPOUT FOR CANS.

Application filed January 23, 1923. Serial No. 614,402.

To all whom it may concern:

Be it known that I, ROBERT KEITH HALL, a citizen of the United States, residing at Denver, in the county of Denver and 5 State of Colorado, have invented certain new and useful Improvements in Collapsible Spouts for Cans; and I do declare the following to be a full, clear, and exact description of the invention, such as will enable others skilled in the art to which it 10 pertains to make and use the same, reference being had to the accompanying drawings, and to the characters of reference marked thereon, which form a part of this specification.

This invention relates to cans and has specific reference to a collapsible spout that can be combined therewith.

It is customary at present to dispense as 20 many things as possible in sealed containers, and among others may be mentioned condensed milk, olive oil, syrup, etc. Referring particularly to the condensed milk and allied products, which are extensively used 25 throughout this country and the world, it is customary to puncture the top of the can on opposite sides of the center, one opening serving to permit the milk to flow out and the other opening serving as an air vent to 30 permit the air to enter as the liquid contents flows out. It is well known to all who have used condensed milk that the above method of emptying the can is open to the objection that milk will flow down the sides of the 35 can and present an untidy and insanitary appearance which is highly objectionable, where the can is used for pouring milk directly into the coffee, as is oftentimes done.

It is evident that a spout in close proximity to the pouring hole would be a great convenience, as it would prevent milk from flowing over the top and down the sides of the can. Attempts to provide cans of the 40 type with spouts have failed because a spout such as is commonly used would have to project upwardly from the top of the can and this would prevent the cans from being adapted to be closely packed in boxes for 45 shipping.

It is the object of this invention to produce a collapsible spout that can be folded against the top of the can during shipment and which can be easily unfolded into operative position when the can is to be used.

In order to describe my invention with 55 greater clearness, I shall have reference to the accompanying drawing, in which:

Fig. 1 shows a perspective view of a can provided with my collapsible spout which is shown in folded or inoperative position. 60

Fig. 2 shows a view similar to that in Fig. 1, but showing the spout in unfolded or operative position.

Fig. 3 is a top plan view of the can shown 65 in Fig. 2.

Fig. 4 is a plan view of the spout in folded position; and

Fig. 5 is a section taken on line 5—5, Fig. 4.

The same reference numbers will be used 70 to indicate the same parts throughout the several views.

Numeral 1 designates a can of ordinary construction whose top is designated by the numeral 2. Cans of this type are usually so constructed that the top of the sides extend a short distance above the plane of the top, thus forming an upwardly projecting flange 3. My improved spout 4 is formed by means 75 of dies, or otherwise from thin flexible material such as lead or tin-foil, or any other suitable material that will bend without breaking. The spout is preferably made in the shape shown in Figs. 2 and 3 and has two sides 5 and 6 and a bottom 7. The bottom member is not entirely essential, as the lower edges of sides 5 and 6 can be soldered directly to the top 2. It is preferable, however, to have the spout made as shown, as it can be more readily secured to the can top. 80 After the spout has been soldered in place on the can top in the position shown in Figs. 2 and 3, it is folded by bending inwardly and downwardly the side 5 and then bending the side 6 over and downwardly in the manner shown in Figs. 1, 4 and 5. The spout when in collapsed position is of less thickness than the height of the flange 3 and therefore does not interfere with the stacking of the cans on a counter or in a box. 85

When the contents of the can is to be used, the cook merely takes a sharpened instrument such as a fork tine or a nail and lifts up sides 6, after which side 5 is unfolded. The spout is then smoothed into the shape 90 shown in Figs. 2 and 3. Two holes 8 and 9 are then punched on opposite sides in the manner shown. Hole 9 is preferably 100

punched near the inner corner of the spout. It is now evident that the contents of the can may be poured out through the hole 9 and that it will have to flow over the spout.

5. Although I have described my invention in connection with a condensed milk can, it is evident that it can be used with any liquid and also with cans containing salt or other freely flowing material. Instead of using 10 metal, my spout may be made of paper or cloth, especially when the contents of the can is in powdered form.

Having now described my invention, what I claim is:

A can having a flat end wall, a spout of 15 thin flexible material consisting of a triangular shaped base member secured to said flat wall, said base member being bounded on two sides by a continuous upstanding wall, said side walls being capable of being folded 20 flat upon said base member.

In testimony whereof I affix my signature.

ROBERT KEITH HALL.
